UNITED STATES PATENT OFFICE.

RUDOLF RYCHIGER AND ERNST KÜPFER, OF STEFFISBURG, SWITZERLAND.

APPARATUS FOR PRODUCING EDGED WORK ACCORDING TO A PATTERN.

1,405,743.

Specification of Letters Patent.

Patented Feb. 7, 1922.

Application filed July 14, 1919. Serial No. 310,664.

To all whom it may concern:

Be it known that we, RUDOLF RYCHIGER and ERNST KÜPFER, both Swiss Confederates, and residents of Steffisburg, Switzerland, have invented new and useful Improvements in Apparatus for Producing Edged Work According to a Pattern, of which the following is a specification.

It is already known that in apparatus for turning according to a pattern, the tool holder is caused to reciprocate against the work which rotates with the machine spindle, and is simultaneously caused to oscillate, whereby the cutting tool cuts out from the work a profile depending upon the form of the pattern. It has not, however, been hitherto possible to produce with such apparatus edged work in which straight cut surfaces are connected by sharp edges.

20 The subject matter of the present invention is an apparatus for producing edged work in which a copying lever performing movements to correspond with the tool, is caused to reciprocate by means of a pattern, 25 and is caused to oscillate. The novelty consists in that the copying lever is always maintained parallel with one of the straight sides of the pattern, and tips over the edges of the pattern with great speed.

30 A form of construction of the invention is illustrated by way of example in the accompanying drawing, in which—

Figure 1 is a partial vertical section on the line A—A of Figure 2,

35 Figure 2 is a plan,

Figure 3 is a front elevation.

The pattern used, with the apparatus as illustrated, consists of a square plate 1, to which four bolts 2 and a quadrangular frame 3 are fixed. A roller 2' is rotatably mounted on each bolt 2. The boss 4 is provided centrally in the plate 1, and serves securely to mount the plate upon a machine spindle 5. The spindle 5 passes through 40 the bearing 6 and carries at one extremity a frame 7. A double armed copying lever 8 rests against two of the rollers 2'. The copying lever at its pivoting point is fixedly mounted upon a spindle 9. An arm 10 45 which extends over the frame 3 is carried by the copying lever. This arm carries a roller 11 which travels along the inner periphery of the frame 3. The spindle 9 rests in a bearing 12. A one-armed tool holder 13 is mounted upon the end of the spindle 9, which projects beyond the bear-

ing. This tool holder holds a tool 14 at its free end. A spiral spring 15 is placed upon the bearing 12. An upwardly extending part 16 of the spiral spring engages, 60 with one arm, the copying lever 8, thereby causing the lever to be pressed against the roller 2' of the pattern 1. The bearing 12 is disposed at the end of a slide 17. This slide moves in the direction of the arrow 19, and serves to bring forward a cylindrical rod 20, which passes into the sleeve 18' attached to the guide 18. A spiral spring 21 mounted on the rod 20 at one end presses against a projection or stop 22 provided in 70 the sleeve 18', and at the other end against a head 23 screwed to the rod 20. The bearing 6 is disposed upon the upper side of the guide 18. The latter may for example be fixed to the face of a machine tool in any 75 suitable manner.

The apparatus above described operates as follows:

By moving the pattern 1, the copying lever 8 is positively actuated and makes a 80 reciprocating movement in the direction of the arrow 19, with the slide 17, and simultaneously rotates about the spindle 9 in the direction of the arrow 25.

The spindle 9 communicates the oscillations of the copying lever 8 to the tool holder 13, which is disposed upon the same spindle, and therefore also reciprocates.

Upon rotation of the pattern, the lever 8 always assumes a position, being guided on the frame 3 (rollers 2'), parallel to that side of the frame which is turned towards the lever, and thus the tool holder 13 and the tool 14 are always held in one uniform working position, and in the present case at 90 a right angle to the side of the hole to be cut. As the distance 27 from the axis of the spindle 9 to the cutting edge of the tool 14 (Fig. 2) is equal to the distance 28 (Fig. 1) from the axis referred to, to the 100 axis of rotation of the roller 11, the tool 14 cuts a square opening in the work or plate 26, which is firmly clamped upon the frame 7. The length 29 (Fig. 3) of the cut-out opening corresponds to the distance traversed by the axis of rotation by the roller 11 along one side of the frame 3.

The pattern may be set beyond the range of the machine spindle 5, and have a different speed of rotation from the latter. 110 Thus if the tool acts upon the work with the pattern illustrated in the drawings, the

pattern having twice the number of revolutions of the machine spindle, an octagon would be produced.

It is understood that the pattern may have other shapes than that illustrated.

We claim:

Apparatus for producing edged work according to a pattern, which is connected to the rotating machine spindle and causes the movement in a transverse direction of a copying lever that moves with the tool and is caused to oscillate, comprising a polygonal pattern provided with a guide frame having inner and outer edges, a copying

lever contacting with the outer edges of 15 said guide frame, an arm on said lever contacting with the inner edges of said guide frame in such a manner that the copying lever is always set parallel with one or other of the straight sides of the guide frame and 20 spring means to cause the rapid tipping over of the lever around the corners of the pattern guide frame.

In testimony whereof we affix our signatures.

RUDOLF RYCHIGER,
ERNST KÜPFER.
